UNITED STATES PATENT OFFICE.

EDWARD MARSHALL, OF BIRMINGHAM, COUNTY OF WARWICK, ENGLAND.

SEWING-MACHINE.

SPECIFICATION forming part of Letters Patent No. 239,180, dated March 22, 1881.

Application filed July 19, 1880. (No model.) Patented in England December 12, 1879.

To all whom it may concern:

Be it known that I, EDWARD MARSHALL, a subject of the Queen of Great Britain, residing at Birmingham, in the county of Warwick, 5 England, mechanical engineer, have invented certain new and useful Improvements in Sewing-Machines, (for which I have received Letters Patent in England, No. 5,094, dated 12th December, 1879,) of which the following is a 10 specification.

My invention consists of the following arrangements or combinations of parts for winding cotton, silk, or other thread upon shuttle spools or bobbins used in sewing-machines.

15 On the axis of the driving-wheel, on the outer side, or side opposite the goose-neck of the machine, I place a toothed wheel of smaller diameter than the driving-wheel, so as to be inclosed by the rim thereof, the said toothed 20 wheel turning loosely upon the said axis, and being furnished with a handle for turning it. On the base of the machine is a spring horizontal bolt, which bears against the inner face of the driving-wheel, and which snaps into a 25 hole in the driving-wheel when the said hole is brought opposite to it, and thereby locks the driving-wheel, and through it the other working parts of the sewing-machine. By means of a thumb-plate carrying an incline, the bolt 30 can be turned on its axis, when the said incline, acting on a fixed incline or part on the frame of the machine, withdraws the spring-bolt out of action. The axis of the spool-carrier terminates in a pinion, which, when the 35 spool is placed in the said carrier, is made to gear with the toothed wheel, and by turning the said toothed wheel the winding of the thread upon the spool may be effected. The position of the locking-bolt is such that its 40 thumb-plate must be depressed to permit of the introduction of the spool into the spool-carrier, and when the thumb-plate is in its depressed position the locking-bolt is thrown into action, and locks the driving-wheel and the 45 other working parts of the sewing-machine. When the spool has been filled and removed the raising of the thumb-plate of the locking-bolt throws the said bolt out of action, so that the sewing-machine may be worked, and 50 at the same time shields the spool-carrier from injury.

I will now proceed to describe, with reference to the accompanying drawings, the manner in which my invention is to be performed.

Figures I and II represent longitudinal vertical sections of a portion of a sewing-machine provided with my improvements for winding cotton, silk, or other thread upon shuttle spools or bobbins used in sewing-machines; and Fig. III represents an end elevation of 55 the same. Fig. IV represents, in horizontal section, the locking-bolt, together with its case and thumb-plate. In Fig. I the driving-wheel is represented locked and the spool-carrier in position for work, and in Fig. II the driving-wheel is represented unlocked and the spool-carrier thrown out of gear with its driving toothed wheel.

The same letters of reference indicate the same parts in Figs. I, II, III, and IV.

a is the ordinary driving-wheel on the axis *b*, an inside toothed wheel, *c*, on the said axis *b* transmitting the motion to the working parts of the machine in the ordinary way. *a*² is the handle of the driving-wheel *a*. On the 70 said axis *b* is placed, outside the driving-wheel *a*, or on the side opposite the goose-neck, a driving-wheel, *e*, of smaller diameter. This wheel *e* is inclosed by the rim of the driving-wheel *a* and is free to turn on the 75 axis thereof. It is provided with a handle, *e*², for working. *f* is the shuttle-spool, and *h* is the spool-carrier by which it is rotated. One end of the said spool-carrier *h* has the form of a hollow cone, into which one end or 80 flange of the spool *f* passes, the pivot on the other end of the said spool turning in the bearing *i*. A coiled spring, acting against the conical end of the spool-carrier *h*, presses it outward when at liberty to move, and 85 causes the said spool-carrier to bear forcibly against the flange of the spool *f*, so that the said spool-carrier and spool rotate together. On the other end of the said spool-carrier *h* is a pinion, *k*, which can be made to gear with the toothed wheel *e*, as represented in Fig. I, or be ungeared from the said toothed wheel *e*, as represented in Fig. II. When geared with the wheel *e* the motion of the said wheel *e* may be transmitted to the spool-carrier and spool 90 for winding the silk or other thread upon the spool.

l is a spring horizontal bolt for locking the driving-wheel *a* when the winding mechanism is in use. The said bolt *l* works in a case on the goose-neck or upright *m* of the machine, 5 and the said bolt is pressed outward or into its locking position by the coiled spring represented. When the bolt *l* is at liberty to move it snaps into a hole, at *p*, in the driving-wheel *a*, when the said hole *p* is brought opposite it, 10 as represented in Fig. I. The driving-wheel *a* is thereby locked, and through it the working parts of the sewing-machine. On the end of the bolt *l* is a thumb-plate, *n*, having a cam or incline, at *q*, for withdrawing the bolt *l* when 15 the said thumb-plate is raised into the position represented in Fig. II. The withdrawing of the bolt *l* is effected by the cam or incline *q* on the thumb-plate *n* bearing against the straight face of the upright *m*, as will be understood 20 by comparing the positions of the thumb-plate in Figs. II and IV. In Fig. IV the thumb-plate is represented in its depressed position and the bolt-shot, and in Fig. II in its withdrawn position and its spring compressed. 25 When the thumb-plate *n* is in its raised position, Fig. II, it shields or protects the spool-carrier *h*.

When it is wished to use the machine for winding thread on the shuttle-spool the thumb-plate *n* is turned down into the position represented in Figs. I and IV. The bolt *l* is thereby permitted to take its locking position and lock the driving-wheel *a*, and through the said wheel the working parts of the sewing-machine, and the spool-carrier is uncovered. The 30 spool is next placed in the spool-carrier *h* by pressing the latter inward so as to compress its coiled spring. The pressing back of the spool-carrier causes its pinion *k* to gear with the toothed wheel *e*, as represented in Fig. I, and by now turning the said toothed wheel *e* by its handle *e*² the winding of the thread 35 upon the spool may be effected.

Fig. V represents a side elevation of a portion of a sewing-machine containing a modification of the winding mechanism last described. The winding mechanism represented in Fig. V is especially fitted for use with sewing-machines to be driven by a treadle, or by 40 steam or power other than manual. In this arrangement the spool-carrier *h* and locking-bolt *l* work in cases *h*² *l*², respectively, made on

the outside of the upright *m* of the machine, and the bearing *i* for the spool is carried by the said cases *h*² *l*², instead of by the base-plate 55 of the machine. The cam or incline *q*, for taking the bolt *l* out of its locking position when the thumb-plate *n* is raised, is made on the edge of the case *l*², containing the bolt *l*, a short arm, *n*², on the said thumb-plate *n*, bearing 60 against the cam or incline *q*, as represented. The action of the parts of this arrangement is the same as corresponding parts of the arrangement represented in Figs. I, II, III, and IV.

Having now described the nature of my invention and the manner in which the same is to be performed, I wish it to be understood that I do not limit myself to the precise details herein described and illustrated, as the same may be varied without departing from the nature of my invention; but

I claim as my invention of improvements in sewing-machines—

1. The combination, with the driving-wheel of a sewing-machine, of a gear-wheel supported 75 loosely on the axis of the driving-wheel, on the side opposite the goose-neck, and inclosed by the rim of said wheel, means, as indicated, for imparting independent rotation to said gear-wheel, a spool-carrier, and a gear for imparting motion to the carrier from the aforesaid gear-wheel, substantially as described.

2. The combination of the driving-wheel of a sewing-machine, the independent gear-wheel turning loosely on the axis of said driving-wheel, the spool-carrier, and gear, with a spring locking-bolt, supported on the stationary machine-frame, and adapted to lock the driving-wheel, and through it the other working parts of the sewing-machine, substantially as described.

3. The combination of the spool-carrier, spring-bolt, and thumb-plate, relatively arranged, substantially as described, so that said plate forms a shield to the spool-carrier while holding back the said bolt, but exposes the same on being turned to release the bolt, as set forth.

EDWARD MARSHALL. [L. S.]
